UNITED STATES PATENT OFFICE

107,152

DESIGN FOR A DINING TABLE

George McStay Jackson, Lake Bluff, Ill., assignor to The Hoosier Manufacturing Company, New Castle, Ind., a corporation of Indiana

Application August 23, 1937, Serial No. 71,260

Term of patent 3½ years

To all whom it may concern:

Be it known that George McStay Jackson, a citizen of the United States, residing at 707 Prospect Avenue, Lake Bluff, in the county of Lake and State of Illinois, has invented a new, original, and ornamental Design for a Dining Table, of which the following is a specification, reference being had to the accompanying drawing, forming a part thereof.

The figure is a perspective view of a dining table, showing my new design.

I claim:

The ornamental design for a dining table, as shown.

GEORGE McSTAY JACKSON.
